2 Sheets-Sheet 2

FIG. 3.

A hand-drawn diagram of a U-shaped metal bracket. The bracket has a central vertical leg with a horizontal slot and a circular hole. A screw is shown passing through the slot and into the central leg. The diagram is labeled with the number '26' at the top right and bottom right.

Inventor

E. L. Clark.

By

A stylized, cursive signature of "E. L. Clark" with a large, prominent "A" in the middle. The signature is written over a large, irregular, black, ink-smeared mark that looks like a stylized letter "A" or a checkmark.

Attorney

UNITED STATES PATENT OFFICE

ISRAEL L. CLARK, OF RIVERSIDE, RHODE ISLAND

COLLAPSIBLE DRUM

Application filed October 27, 1927. Serial No. 229,207.

This invention relates to a collapsible drum.

The present invention is adapted particularly to be suspended from the body when marching and when not in use to take up less space and be thinner than an ordinary drum and also to be of such construction as to automatically unfold into operative position when applied to the body.

10 It is aimed to provide a drum which may be readily collapsed and which is relatively light in weight and is primarily adapted to be made of metal so as to present a polished finish.

15 Another object is to provide a novel construction of drum head possessing the advantages and details as hereinafter described and illustrated in accompanying drawings relating to one preferred embodiment.

20 In said drawings:—

Figure 1 is a view in side elevation of the improved drum;

Figure 2 is a top plan view;

Figure 3 is a vertical sectional view taken 25 partly through the drum on the plane of line 3—3 of Figure 1;

Figure 4 is a view similar to Figure 3 but with the drum parts retracted, and

Figure 5 is a detail sectional view taken 30 on the line 5—5 of Figure 1.

Referring specifically to the drawings, the drum is composed of similar heads at each end as generally designated A. Each head consists of a ring or shell 10 having a smaller 35 outer ring 11 fastened thereto or forming a part thereof. Across the outer end of the shells 10, skins 12 are stretched, whose margins may be fastened around hoops 13 and opposite which detachable securing hoops 14

40 are disposed. The requisite tension or pressure on the skin 12 is imparted by means of securing members B each consisting of hooks 15, respectively engaging the rings 11 and hoops 14, and engaged by threaded ends 16 45 rotatably engaging bearings 16^a, the heads 16^b of said ends 16 being polygonal to for engagement by a suitable wrench or other tool.

Each head has any desired number of 50 snare 17 arranged in coacting relation with

the skins 12. The snares 17 are guided through openings 18 in brackets 19 and through an openings 10^a in hoop 10 and having one of their ends secured to a follower 20 engaging a threaded end 21 that is rotatably mounted in a bearing 21^a secured to ring 11.

The inner surfaces of the shells 10 are provided with rings 22 having inturned flanges 24 and adapted to telescope within 60 the shells are body sections 23 having flanges 25 adapted to engage flanges 24. Additional body sections 26 are adapted to telescope within the sections 23 and within each other and a connecting body section 27 is employed 65 therefor, preferably having a port 28 therethrough. The section 27 has oppositely directed flanges 29 engaging flanges 30 on the adjacent sections 26. Sections 26 have interengaging flanges at 31 and also flanges 32 70 engaging flanges 33 on the sections 23. The sections 23, 26 and 27 are preferably made of aluminum and have their exterior surfaces highly polished so as to present a 75 pleasing effect.

The various sections described enable the drum to be collapsed into the form shown in Figure 4, and in such form, the heads may be held together by means of hooks 34, adapted to engage hoops 14 when the drum 80 is collapsed, as shown in Figure 4, 35 designating turn buckles engaging the oppositely threaded ends of said hooks 34 to tighten them in engagement with hoops 14.

If desired, a single head may be used as 85 a complete drum since it is provided with both a pin and with a snare or snares.

Various changes may be resorted to provided they fall within the spirit and scope 90 of the invention.

I claim as my invention:—

1. A drum comprising heads, and relatively rigid body sections connected thereto and adapted to telescope in said heads, and relatively rigid body sections connecting the 95 first mentioned body sections and adapted to telescope therewith.

2. A drum having relatively rigid body sections in telescopic relation, certain of said sections having coacting hook flanges, and a 100

connecting body section engaging adjacent flanges and having its flanges extending in opposite sections.

3. A drum having heads comprising shells, flanged rings on the interiors of the shells, relatively rigid body sections adapted to telescope within the heads having flanges to engage the flanges on the shells, body sections coacting with the first mentioned body sections and adapted to telescope therein, said body sections having coacting hook flanges.

In testimony whereof I affix my signature.
